LUMINOUS SIGN ELECTRODE

Samuel C. Miller, New York, N. Y.

Application February 12, 1938, Serial No. 190,230

8 Claims. (Cl. 176—126)

This invention relates to electrodes; more particularly to electrodes for luminous signs, such as neon sign construction, and to methods of making the same; more particularly, to a metal-to-glass sealed electrode employed in luminous tubes operating with an ionizable inert gas filling, to obtain a gaseous discharge producing a luminous effect under high potential electrical exciting force.

Electrodes employed in electrical discharge devices of the character mentioned, as known to me, have attendant problems in their manufacture and operation in addition to the cost of their production. Such construction usually involves an electrode shell to which there are affixed leads and sealed within a glass envelope. Electrode devices of this character are more particularly illustrated in the patent to Lohman No. 1,739,513 and my Patent No. 2,064,485. The specific features of these described electrodes have been devised to cure problems in operating conditions and in manufacturing operations particularly due to the exposure of the interior and exterior surfaces of the shell electrode within the zone of activity within the sealed glass envelope.

As desirable as these constructions may be, they offer additional problems in cost and construction in order to introduce these assemblies in the final sign in the electrical connections that may be required to conduct the electrical current to the electrodes.

I have discovered that the full benefits of a cup-shaped electrode, sealable directly to glass, may be made available and provide an electrode from metal-to-glass sealing competitively priced with sealed-in glass electrode shells by the employment of heat resisting stainless steels which are characterized by their resistance to oxidation at elevated temperatures necessary for processing the luminous tube assembly and which metal is further characterized by the formation of oxidized scale with great difficulty at high temperatures but which, nevertheless, provides scale of such adherence as not to flake off and interfere with a metal-to-glass seal joint; that is further characterized by a coefficient of expansion suitable for joining to glass of the character employed in neon discharge devices.

Such metal which I have discovered is suitable for the production of cup-shaped metal-to-glass sealable electrodes is exemplified in a heat resisting chromium steel, more particularly a chromium steel having the characteristics identified as Allegheny 55, the typical analysis for

which is more specifically described in Bulletin 55, Allegheny Steel Co. 1934, and includes from 23 to 30% of chromium, with carbon .25%, manganese 1.00%; phosphorus .025%; sulphur .025%, silicon .50% and the balance iron.

This metal, I have further discovered, is readily wetted by fused glass at temperatures necessary for working glass of the character employed in neon discharge tube signs and has sufficient resistance to deformation at temperatures necessary for processing by bombarding the completed and sealed discharge tube assembly.

Apart from the discovery hereinabove mentioned, my invention resides in the provision of a cup-shaped electrode of a configuration amenable to effecting a seal of glass-to-metal by commercial quantity productive methods, to provide a competitive item with the sealed-in glass shell electrodes.

A still further object of my invention resides in the provision of a luminous or gaseous discharge tube electrode assembly comprising a deep draw cup-shaped electrode of metal sealed to glass, which makes for compactness and economy in construction, while not diminishing the surface area of the electrode, thereby to give long life, as required in the trade, and further to minimize sputtering, which interferes with refinements in working conditions, particularly in connection with fluorescent tubes, where the sputtering effect would defeat and destroy or reduce the life of tubes of such character.

Other objects of my invention reside in the provision of an electrode assembly and a method of assembly which effects material economies by simplification of construction while achieving long life and extended performance in operation.

To attain these objects and such further objects as may appear herein or be hereinafter pointed out, I make reference to the accompanying drawings, forming a part hereof, in which—

Figure 1 is a fragmentary, longitudinal sectional view of the parts for making the electrode, in accordance with one embodiment of my invention;

Figure 2 is a fragmentary longitudinal sectional view, with the parts connected and sealed together;

Figure 3 is a section taken on the line 3—3 of Figure 2;

Figure 4 is a fragmentary longitudinal sectional view of another embodiment of my in-

vention, showing the parts immediately before assembly;

Figure 5 is a fragmentary longitudinal sectional view of the parts illustrated in Figure 4, brought together and assembled;

Figure 6 is a fragmentary longitudinal sectional view of the embodiment illustrated in Figures 1, 2 and 3, assembled in position with an electrode insulator housing;

Figure 7 is a fragmentary longitudinal sectional view of another embodiment of my invention;

Figures 8, 9 and 11 are fragmentary longitudinal sectional views of three additional embodiments of my invention;

Figure 10 is a section taken on the line 10—10 of Figure 9;

Figure 12 is a section taken on the line 12—12 of Figure 11.

Referring now to the drawings, my invention in an embodiment thereof amenable to quantity production methods for the production of a metal-to-glass seal, deep-draw shell electrode, in which the requisite electrode area is provided in respect of the diameter of the glass tube for luminous discharge tubes, is illustrated in Figures 1 to 3.

In this construction, the proportions of the parts are shown for joining approximately a 15 mm. diameter glass tubing 10, to a shell electrode 11. The shell electrode is cup-shaped and has cylindrical walls 12 and a bottom 13 of integral construction, joined to each other by the rounded edge 14, during the drawing operation, employing a metal more specifically hereinafter described.

Adjacent the mouth or opening 15, the walls 12 are provided with a flare portion 16. The extensiveness of the flare is calculated to have the smallest diameter adjacent the throat 17 slightly smaller than the outer diameter of the tubing 10. The diameter of the mouth 15 is slightly larger than the outer diameter of the tubing 10, with such tolerance as to take care of the variation in size encountered in connection with the tubing 10, and such variations in roundness as may be encountered in the trade in connection with glass tubing used for luminous sign constructions.

With these parts so provided, and the shell 11 mounted upon a glass worker's lathe, a section of tubing 10 may also be mounted upon a chuck of a glass worker's lathe equipped with blowing means, and while the shell 11 and the tubing 10 are heated adjacent the mouth 15 and the edge 18 by the glass worker's flame, the parts are brought together until the edge 18, nests within the flare 16. A joint 19, as illustrated in Figure 2, will thereby be obtained, of intimate and secure contact. The flare in relation to the edge 18 of the tubing provides for a wiping action between the glass and the flared portion of the shell, to give the requisite wetting action of the glass upon the metal. The minimum amount of attention is required by the glass blower or the minimum amount of accuracy is required in aligning the parts of the glass worker's lathe where automatic machinery may be employed, as any variation in size of the glass in its diameter, as may be encountered in its production or by reason of its fusion during operation will be accommodated by the flare 16 in bringing these parts together in the joining of the two at the fusion or melting temperature. An efficient and effective seal is thereby provided, par-

ticularly suitable for production methods, not only in the effecting of the seal but the requisite rigidity of the seal is maintained in the subsequent bombarding process after the section of the tubing 10 is joined to the glass lettering forming the luminous sign.

Thus, after producing the metal to glass seal, as illustrated in Figure 2 and the joining of the section of the glass 10 at its open end to a glass tubing sign assembly, the sign is processed by evacuating the air and heated to the point where all the impurities are driven out of the inside of the tubing. The electrodes are connected to a high voltage transformer while drawing out the air, until a discharge takes place between the electrodes. During this operation, the metal is brought to a bright red heat, approximately 900° C., and the juncture of the glass to metal must be sufficient to prevent collapsing of the glass as well as the metal. The employment by me of the tapered or flared glass to metal juncture and the cup-shaped electrode of the metal hereinafter to be more specifically described, assures a maintenance of the seal during this rigid processing operation. This I attribute not only to the formation of the seal as already described, but also to the characteristics of the cup-shaped metal electrode which I have provided.

When so assembled as part of a sign and associated with the sign frame 20, the electrode housing insulator 21 and pressed against the contact spring 22 of an assembly more specifically described and illustrated in my Patent No. 2,046,960, July 7, 1936, an exceedingly compact arrangement is provided in that the shell 11 may be brought into immediate contact with the contacting spring 22 without any further provision for bringing these members into electrical conducting and contacting connection.

The depth of the cup-shaped electrode provides all of the requisite surface area on the interior surface of the assembly, to give the long life and requisite discharge for maintaining operating conditions for luminosity. The likelihood for sputtering is minimized and where the sign assembly is used in connection with fluorescent glass tubing or glass tubing coated with fluorescent compositions, the elimination of sputtering in conjunction with any mercury vapor yet further insures long life of fluorescent signs.

While I have described and illustrated in Figures 1, 2 and 3, my preferred construction which is most amenable for quantity production methods in the formation of the seal joints of glass to metal and for other purposes hereinbefore described, an important contributing factor of my invention lies in the discovery of a commercially practical metal from which the cup-shaped electrodes may be formed. Accordingly, where quantity production methods for forming the juncture or seal between the glass and metal are not of vital moment and where it may be desired to obtain some of the features of my invention, a simple cylindrical shell 23 may be provided. This shell differs from that heretofore described in that no flare need be provided at the mouth or adjacent the edges 24. The metal throughout may be of uniform thickness where I employ a shell made from Allegheny—55 metal, hereinbefore described, and which, for purposes of reference, I will designate as "heat resisting, drawn, chromium steel."

The preferred alloy constitution of Allegheny—55 has already been given and while this metal is known to resist high heat, it has never been

employed for the purposes discovered by me in that this metal has been regarded as not suited for deep drawing. Any contour which involves difficult fabrication steps, such as deep drawing operations, has not been regarded as the field for the employment of Allegheny-55 or similar heat resisting chromium steel. However, extended efforts involving more or less minute progressive changes in forming this metal have led to the discovery of the successful adaptation of this metal for deep draw, cup-shaped electrodes in which the full rigidity of the metal may be employed without resorting to the need for tapering the metal itself in order to provide what is generally referred to as a Housekeeper seal.

Thus in the embodiment illustrated in Figure 7, the walls of the shell 23 may be maintained of uniform thickness to the edges 24 where heat resisting, drawn chromium steel of the character herein described is employed. With such shell, the tubing 10a may be brought together with the shell 23 to form the seal 19a, in which the glass is fused on the exterior and interior surfaces. The uniform depth D of the metal throughout its length, to and including the edges 24, provides a rigid joint of requisite strength which has heretofore rendered the tapered metal employed in Housekeeper seals impractical.

During the processing step or bombarding step in making the complete seal wherein the metal is almost brought to a bright red temperature, the thickness D of the metal, at the point where it is embedded in the glass at the joint 19a, will prevent collapsing of the metal to glass juncture. Thus, where speeds of operation and production for making the seal of glass to metal are not of vital moment, the employment of the heat resisting drawn chromium steel of the character herein described, especially using the uniform thickness of metal D to and including the edges 24, makes possible the employment of this metal for a metal to glass seal while utilizing the extended area as obtained by a deep draw shell.

For other embodiments of my invention particularly conducive to quantity production methods, I have illustrated other forms of deep draw shell electrodes for the formation of metal to glass sealable electrodes.

In Figures 4 and 5 there is described a shell electrode 11b, in which a tapered section 16b is formed from the throat 17b.

In joining a tubing 10b with the cup-shaped electrode 11b of the character described, during the sealing operation involving the heating of the glass and metal adjacent the edge 18b and the mouth 15b, the shell electrode is nested to contact with the interior surface of the tube 10b to provide a joint 19b, more specifically illustrated in Figure 5.

Here again, wide tolerance in sizes is permissible to make possible speeds of production practical for economical operation, and a thorough wetting of the glass to the metal, to give the desired weld due to the wiping action encountered in the tapered joint 16b and the flare given to the glass in joining the glass tubing 10b to the shell 11b.

Where employing tubing of about 15 mm. diameter, it may be desirable during the processing or bombarding operation, to use a current not in excess of 200 milliamperes, where the duration of the processing operation is of such character as may affect the glass at the joints between the metal and glass. Where the duration of time is of more extended character or the current

through the tubing, during the processing or bombarding operation, is around 300 milliamperes, it may be desirable, especially where the joint is of the type where the metal is on the interior of the glass, to provide a surface configuration of the shell to minimize the attack of the discharge upon the glass at the point of contact of the metal.

For this purpose, reference is made to the embodiments illustrated in Figures 8 to 12, the constructions whereof have been devised to use the high currents specified, or longer durations of time of treatment, and to minimize any adverse effect upon the juncture of the metal to glass.

15 In the embodiment illustrated in Figure 8, a shell electrode 11c is employed, of the general character illustrated in Figures 4 and 5. In this construction, however, the tapered portion 16c is extended to leave a lip 15c, spaced from the 20 interior wall of the glass tubing 10c. This constricted mouth, spaced from the juncture of the glass to metal 19c, allows the discharge during the processing or bombarding operation to go inside the shell and minimize the temperature at 25 the juncture 19c.

Another form of construction to minimize the temperature at the glass juncture is illustrated in Figure 9 wherein an electrode shell 11d is provided at its mouth with a flange 16d, substantially at right angles to the wall of the shell 11d. Here the metal to glass joint 19d may be formed by a pressing operation of the edge of the glass 18 to the flange 16d, to obtain a lap joint and a butt joint instead of the tapered lap joint of the 35 embodiments illustrated in Figures 1 to 5 and 8.

In Figures 11 and 12 I have illustrated a shell electrode of the same general character as described in connection with Figures 1, 2 and 3. For purposes of minimizing the discharge and increase in temperature adjacent the juncture 19, 40 I provide a deflecting member 25, in the form of a rod, extending axially in the shell electrode 11e so that its end 26 is adjacent the mouth of the shell and its opposite end 27 contacts the bottom 45 13e. I may affix the rod 25 in any suitable manner, preferably by spot welding the end thereof 27 to the bottom 13e, as shown at the point 28.

In operation, during processing or bombarding, especially employing the current through the tubing around or in excess of 300 milliamperes, the heat of the discharge will be absorbed first by the rod 25, to minimize the high temperature adjacent the juncture 19, made by metal to glass by the gradual conduction of the heat incident to 53 the bombardment from the rod and then through the shell.

It will thus be observed that I have provided a new and novel electrode of simple and compact construction incident to the discovery of the employment of the cup-shaped heat resisting drawn chromium steel electrode, and its rigidity during process, where employing this metal for glass to metal sealing, especially where I am enabled to eliminate thin sections of metal at the juncture 60 of the seal. It will further be observed that I have provided a form of electrode amenable to quantity production methods and which embodies compactness of construction, effecting material economies in the manufacture of this form 65 of device.

It will also be observed that by the construction herein provided, difficulties which are involved in sealed-in-glass shell electrodes, such as sputtering effects, are overcome, and that my construction avoids the need for special consid-

eration in connection with such devices, in order to prolong their useful life.

Having thus described my invention and illustrated its use, what I claim as new and desire to secure by Letters Patent, is—

1. In a luminous discharge device including a glass tubing envelope, drawn adjacent one end section to a substantially uniform diameter, said end section whereof includes sealed thereto a substantially cylindrical, cup-shaped metal electrode of heat resisting chromium steel drawn to substantially uniform thickness having a portion thereof adjacent the mouth normally displaced and to which displaced portion the glass is sealed in wiping lap-joint contact, the direction and extensiveness of said displaced portion providing a sealed portion making a juncture compensating for a wide tolerance in the glass tubing by being displaced at an angle in respect of the walls of the electrode, the electrode exposing on the interior surface an effective area for long life maintenance, the diameter of the glass tubing being of a size at least a portion of which is within the minimum displaced portion of the electrode, whereby the electrode and tubing are coaxially aligned by the said lap joint.

2. In a luminous discharge device including a glass tubing envelope, drawn adjacent one end section to a substantially uniform thickness, said end section whereof includes sealed thereto a substantially cylindrical, cup-shaped electrode of heat resisting chromium steel drawn substantially to uniform thickness having a portion adjacent the mouth thereof normally flared, and to which flared portion the glass is sealed, in wiping lap-joint contact the direction and extensiveness of said flared portion providing a sealed portion making a juncture compensating for a wide tolerance in the glass tubing, the electrode exposing on the interior surface an effective area for long life maintenance, the outside diameter of said glass tubing, at its entrance end section being at least greater than the inner diameter of the cylindrical portion of said electrode, whereby the electrode and tubing are coaxially aligned.

3. In a luminous discharge device including a glass tubing envelope, drawn adjacent one end section to a substantially uniform diameter, said end section whereof includes sealed thereto a substantially cylindrical, cup-shaped metal electrode of heat resisting chromium steel drawn substantially to a uniform thickness, having a portion thereof adjacent the mouth normally displaced at an angle to form a taper, to the exterior portion of which taper the glass is sealed by a wiping lap-joint, the direction and extensiveness of said taper providing a sealed portion making a juncture compensating for a wide tolerance in the size of glass tubing, the electrode exposing on the interior surface, an effective area for long life maintenance, the diameter of the glass tubing being of a size at least a portion of which is within the displaced portion of the electrode.

4. In a luminous discharge device including a glass tubing envelope, drawn adjacent one end section to a substantially uniform diameter, said end section whereof includes sealed thereto a substantially cylindrical, cup-shaped metal electrode of heat resisting chromium steel drawn substantially to a uniform thickness, having a portion thereof adjacent the mouth normally displaced at an angle to form a taper, to the exterior portion of which taper the glass is sealed by a wiping

lap-joint, the direction and extensiveness of said taper providing a sealed portion making a juncture compensating for a wide tolerance in the size of the glass tubing, the electrode exposing

5 on the interior surface, an effective area for long life maintenance, the tapered portion including a lip inwardly of the seal, the diameter of the glass tubing being of a size at least a portion of which is within the displaced portion of the electrode.

10 6. In a luminous discharge device including a glass tube envelope of substantially uniform diameter and wall thickness, an end section whereof includes sealed thereto by a wiping lap-joint a substantially cylindrical cup-shaped metal electrode of heat resisting steel drawn substantially to a uniform thickness, the walls of the electrode being substantially uniform throughout, the mouth of said electrode being normally flared, 15 the glass being sealed to the interior surface of said flare portion of said electrode by a wiping lap-joint, the direction and extensiveness of the flared portion compensating for a wide tolerance in size of said tube, the juncture of said seal of glass to metal being substantially in line with the interior surface of the walls of said electrode, the outside diameter of the said glass tubing being at least greater than the inner diameter of the cylindrical portion of said electrode.

20 7. In a luminous discharge device including a glass tubing envelope, an end section whereof includes sealed thereto a substantially cylindrical cup-shaped metal electrode of heat resisting steel drawn substantially to a uniform thickness having a portion thereof adjacent the mouth flared, and to the interior surface of which flare is sealed the glass by a wiping lap-joint, the direction and extensiveness of said flare making a juncture compensating for a wide tolerance in glass tubing, 25 and a heat conducting baffle coaxially disposed in said electrode.

30 8. In a luminous discharge device including a glass envelope, an end section whereof includes sealed thereto a substantially cylindrical cup-shaped metal electrode of heat resisting steel drawn substantially to a uniform thickness a portion thereof adjacent the mouth being normally displaced outwardly, and to which the glass tubing is sealed by a wiping lap-joint, the direction and extensiveness of said outwardly displaced portion forming a juncture displaced out of the plane of the interior surfaces of the electrode, the outside diameter of said glass tubing being at least greater than the minimum internal 35 diameter of the electrode.

40 9. In a luminous discharge device, a substantially cylindrical cup-shaped metal electrode of heat resisting chromium steel drawn substantially to a uniform thickness, the thickness of the walls of said electrode being uniform throughout the depth of said electrode, providing an extended area on the interior thereof to give long life operating conditions, the mouth portion of said electrode being normally outwardly flared of extensiveness and direction to provide a contacting surface for sealing to provide a sealable juncture outside the plane of the side walls of said electrode and for forming a wiping lap-joint seal between its surfaces and the glass tubing, and including a coaxially disposed heat conducting baffle member attached to the bottom of said electrode at its interior face.
